UNITED STATES PATENT OFFICE

HARVEY H. BROWN, OF GRAND RAPIDS, MICHIGAN.

SIFTING-MACHINE.

1,072,816.

Specification of Letters Patent.

Patented Sept. 9, 1913.

Application filed September 28, 1912. Serial No. 722,816.

To all whom it may concern:

Be it known that I, HARVEY H. BROWN, a citizen of the United States of America, residing at Grand Rapids, in the county of Kent and State of Michigan, have invented 5 certain new and useful Improvements in Sifting-Machines; and I do hereby declare the following to be a full, clear, and exact description of the invention, such as will enable others skilled in the art to which it 10 appertains to make and use the same.

My invention relates to improvements in sifting machines, and more particularly to machines for sifting ashes, and its object is 15 to provide a device that will retain the dust within the same, and that will effectually separate the ashes from the cinders and partially burned fuel, and to provide the device with various new and useful features hereinafter more fully described and particularly pointed out in the claims.

My invention consists essentially of a closed case having a hopper above the same and provided with a lid to close the same, 25 and a slide to control the flow therefrom into the case; an inclined screen in the case, means for vibrating the screen, a compartment in the case to receive the material that does not pass through the screen, and 30 another compartment in the case containing a drawer to receive the material that passes through the screen, and means for removing the contents of the case, as will more fully appear by reference to the accompanying 35 drawings, in which:—

Figure 1 is a longitudinal vertical section of a device embodying my invention; Fig. 2 a transverse section of the same on the line 2—2 of Fig. 1; and Fig. 3 is a sectional detail on the line 3—3 of Fig. 1.

Like numbers refer to like parts in all of the figures.

1 represents a rectangular case of any suitable dimension, preferably square in 45 cross section and of greater length than width, 2 is a hopper mounted on the case having an opening at the bottom, and provided with a slide 3 to close said opening more or less to regulate the flow from the 50 hopper into the case, or to shut off the flow as occasion may require. The hopper has a cover 2^a hinged thereto whereby the same may be closed to retain the dust or ashes, 4 is an inclined screen in the case below the 55 hopper and above the drawer 5 removable from the case. This screen at its lower end

projects over a partition 6 extending upward from the bottom of the case to near the screen and spaced apart from the rear end of the case to form a receptacle to receive the 60 cinders and partially burned fuel or other like material too large to pass through the screen.

7 is a slide in the bottom of the case which when drawn out leaves an opening to discharge the contents of said receptacle.

8 represents two crank shafts journaled in the case the crank portions thereof projecting upward and connected by rods 9. These crank shafts support the screen 4 and 70 oscillate in arcs about their axes where journaled in the case.

To prevent material from escaping over the upper end of the screen, an angle bar 11 extends transversely across its upper end, 75 and its attached thereto. To prevent escape of material at the edges of the screen angle bars 12 are fixed on the inside of the case above the screen and project over the edges of the screen.

To oscillate the screen a rotating crank shaft 10 is journaled in the case and projects outside the same and is provided with a handle for manually rotating said shaft. This shaft is connected by a rigid arm to 85 the angle bar 11, the screen being flexible in the portion extending between the crank shaft 8 and the bar 11, whereby when the shaft rotates the flexibility of the screen permits the arm and crank to rotate. This 90 movement together with the arcuate movement of the oscillating crank shafts 8 imparts to the screen a compound longitudinal and vertical movement, whereby the material thereon is quite effectually acted upon to sift the same, and also to cause the portion that will not pass through the screen to traverse the screen and escape from the lower end thereof.

What I claim is:—

1. A sifting machine, comprising a closed case, a hopper above the case and communicating therewith, a screen in the case below the hopper inflexibly supported throughout a portion of its length and flexible at one 105 end, means for movably supporting the screen, a rotating crank shaft, and means for directly connecting the flexible end of the screen and the crank portion of the aforesaid shaft, and means for manually 110 rotating said shaft.

2. A sifting machine, comprising a case,

100

105

110

- a hopper above the case, a slide to control the flow from the hopper to the case, an inclined and movably supported screen beneath the hopper having a flexible projecting end, oscillating crank shafts supporting the screen, a manually rotated crank shaft, and an arm rigidly connecting the crank portion of the shaft and the flexible end of the screen.
- 10 3. A sifting machine, comprising a closed case, a hopper above the case, means for controlling the flow from the hopper to the case, an inclined frame below the hopper, a screen attached to the frame and having a flexible end projecting from one end of the

frame, oscillating rock shafts supporting the frame, an angle bar fixed on the upper end of the screen, a manually rotated crank shaft near the angle bar, and means for directly connecting the said crank shaft and the angle bar whereby the angle bar and end of the screen follow the movement of the crank. 20

In testimony whereof I affix my signature in presence of two witnesses.

HARVEY H. BROWN.
